Patented Sept. 21, 1915.

Inventor
FRANK MACEY

By *Watson E. Coleman*
Attorney

UNITED STATES PATENT OFFICE.

FRANK MACEY, OF GOVANS, MARYLAND.

HORSESHOE-CALK.

1,154,330.

Specification of Letters Patent. Patented Sept. 21, 1915.

Application filed July 6, 1915. Serial No. 38,241.

To all whom it may concern:

Be it known that I, FRANK MACEY, a citizen of the United States, residing at Govans, in the county of Baltimore and State 5 of Maryland, have invented certain new and useful Improvements in Horseshoe-Calks, of which the following is a specification, reference being had to the accompanying drawings.

10 This invention relates to an improved horseshoe calk and has for its primary object to provide a device of this character which may be easily and quickly attached to the ordinary horseshoe to prevent the horse 15 from slipping or falling on smooth or ice-covered road surfaces.

It is another important object of the invention to provide a detachable horseshoe calk which is applicable to horseshoes of 20 various width and thickness without necessitating any changes whatever in the form or construction thereof and which will positively retain its applied position upon the shoe.

25 It is another and more specific object of my invention to provide a device of the above character including a calk body, and separable clamping members for engagement with the shoe coöperating with the opposite 30 side faces of said body and exerting a wedging action thereon to retain said body in gripping engagement upon the bottom surface of the shoe.

The invention has for an additional object 35 to provide a detachable horseshoe calk which is simple and inexpensive in its construction and embodies certain structural features which afford a maximum range of adjustment of the several coöperating parts.

40 With the above and other objects in view, my invention consists in the novel features of construction, combination, and arrangement of parts to be hereinafter more fully described, claimed and illustrated in the accompanying drawing, in which,

Figure 1 is a perspective view showing my invention in its preferred form, applied to a horseshoe; Fig. 2 is an enlarged vertical transverse section; Fig. 3 is a section taken 50 on the line 3—3 of Fig. 2; Fig. 4 is a detail perspective view of the calk body; Fig. 5 is a similar view of one of the clamping members; and Fig. 6 is a perspective view showing a slightly different form of the invention.

55 Referring in detail to the drawing, 5 design-

nates the body of the calk which is preferably of V or wedge-shaped form having the opposite convergently disposed side faces shown at 6 terminating in the point or gripping edge 7. The other opposite side faces of the calk body are also convergently disposed toward the point or gripping edge 7, as indicated at 8. Upon the wider or base end of this triangular shaped body, the same 60

is formed with the laterally projecting flanges 9 which extend outwardly over the side faces 6. The surface of this widened base of the calk body has intersecting grooves 10 cut therein so that the same is 70

roughened for engagement with the bottom face of the shoe bar. For the purpose of easily and quickly attaching the body of the calk to the shoe, I provide the clamping members 11. Each of these clamping members 75

consists of a steel body 12 which is of tapering form and is provided with an inner or inclined beveled face 13 for engagement against one of the inclined side faces 8 of the body 5. Upon the wider end of the body 12 80

of the clamping member, the longitudinal projection 14 is formed, and this projection is provided at its extremity with an inwardly disposed flange 15 which has a beveled or sharpened edge 16. Each of the clamping 85

members is also provided with a short longitudinal slot 17 for a purpose to be later referred to, and upon the opposite longitudinal edges of the clamping member, at the inner end of the projection 13, the obliquely 90 inclined lugs 18 are integrally formed. It will be observed that the overhanging flanges 9 on the calk body are of greatest thickness at their central portions and gradually taper or curve upwardly at their opposite ends. 95

Against these tapering surfaces of the flanges 9, the lugs 18 on the clamping members are adapted to bear. The calk body 5 is provided with an opening 19 which is designed to receive the bolt 20. This bolt is 100 adapted to be extended through the slots 17 in the clamping members and the opening 19 in the calk body, and the wall of the slot in one of the clamping members is formed with a countersink to receive the tapering 105 head on one end of the bolt 20, so that the face of the clamping member and the head of the bolt will be flush. A nut 21 is adapted to be threaded on the other end of the bolt for engagement against the other of the 110 clamping members.

For the purpose of obviating all possibil-

ity of longitudinal shifting movement of the clamping members upon the edges of the shoe bar, I provide upon the inner faces of the longitudinal projections 13 on said 5 clamping members, a series of longitudinal V-shaped ribs or teeth 22. The points or apexes of these teeth on one member are disposed on a slightly concave arc while the points of the teeth on the other clamping member are on a slightly convex arc, it being understood that such an arrangement of the teeth is necessary in order to assure their proper clamping engagement upon the inner and outer curved edges of the shoe bar.

15 In assembling the several parts of the device upon the shoe, the clamping members 13 are engaged against the opposite beveled faces 8 of the calk body and the bolt 9 inserted. The clamping members are adjusted longitudinally of the bolt and the flanges 14 thereon engaged over the upper edge of the shoe bar, indicated at S, between the same and the animal's hoof. The nut 21 is then threaded inwardly upon the end of the bolt 21 and the clamping members 13 drawn tightly against the inclined faces 8 of the calk body while the vertical teeth 22 of the clamping members bite into the opposite edges of the shoe. As the inclined inner faces 12 of the clamping members bear against the inclined faces 8 of the calk body, they exert a wedging action on the latter and tend to force the same inwardly between the clamping members so that the roughened 35 base surface 10 of the calk body is caused to frictionally engage the surface of the shoe.

30 After the parts have thus been tightly clamped against the shoe bar, the lugs 18 are struck with a hammer or sledge and forced 40 against the inclined end surfaces of the flanges 10 on the calk body, and serve as an additional means of security for said body to rigidly hold the same in position against the face of the shoe. It will be observed 45 that the gripping point 7 on the calk body projects beyond the points of the clamping members 13 when the several parts are applied and securely clamped upon the shoe so that there will be no wear upon said clamping members and the point of the calk can also be properly sharpened when necessary.

50 In Fig. 6 of the drawing, I have illustrated an alternative construction wherein the inwardly projecting lugs 19 above referred to on the clamping members are omitted. In both forms of the device, however, the separable clamping members are employed to exert a wedging action against the body of the calk and while the latter form 60 of the device is somewhat simpler and may be manufactured at slightly less cost, the provision of the lugs 18 is, nevertheless, believed to be very desirable, as it provides a simple and effective means for assuring absolute security of the body of the calk by

causing a gripping or biting engagement of the roughened face 10 of the calk body upon the surface of the shoe.

From the above description, taken in connection with the accompanying drawing, it will be seen that I have produced a simple, effective and serviceable detachable calk for horseshoes, the several parts of which may be formed from cast steel, iron or other metals.

It will also be noted that the construction and arrangement of the clamping members with respect to the calk body affords a maximum range of adjustment for said members so that the device can be applied to horseshoes of various widths and

thicknesses, and without requiring any alterations whatever in the construction of the ordinary shoe.

By providing a plurality of surfaces for gripping engagement upon the shoe, the device, when properly applied, will absolutely maintain its position and not shift longitudinally upon the shoe.

Any desired number of the calks may be employed and, in view of the adjustability of the clamping members 13, the device can be applied to the toe of a shoe having a lug provided thereon.

The device can, of course, be made in various sizes, and the parts also altered in shape and relative proportion while retaining the advantages incident to the invention.

The device is also susceptible of several modifications and it will, therefore, be understood that I reserve the privilege of adopting all such legitimate alterations as may be fairly embodied within the spirit and scope of the invention as

claimed.

Having thus fully described my invention, what I desire to claim and secure by Letters Patent is:

1. A detachable horseshoe calk comprising a pyramidal-shaped body, clamping members for engagement upon opposite sides of the shoe co-operating with said body to force the same into frictional engagement with the bottom face of the shoe, and means holding said clamping members and the calk body in assembled relation and permitting of their relative longitudinal movement.

2. A detachable horseshoe calk including a pyramidal-shaped calk body, clamping members for engagement upon opposite sides of the shoe to co-operate with the opposite faces of said body and force the same into frictional engagement with the bottom face of the shoe, and means extending through the calk body and the clamping members to hold the same in assembled relation, said clamping members being provided with means whereby the same may be adjusted longitudinally upon said connecting means with respect to the calk body.

3. A detachable horseshoe calk including a pyramidal-shaped calk body having a base of a width substantially equal to the width

- of the shoe, clamping members adapted for engagement upon opposite sides of the shoe and coöperating with the opposite faces of the calk body to force the same into frictional engagement with the bottom face of the shoe, a bolt extending through the clamping members and the calk body to hold the same in assembled relation, and a nut threaded upon one end of said bolt. 5
- 10 4. A detachable horseshoe calk including a calk body having opposite convergently inclined faces, clamping members also having inclined faces to co-act against the respective inclined faces of said calk body, said body being provided with a bolt receiving opening and each of the clamping members having a longitudinal slot to coincide with said opening, a bolt extending through said opening and slots, and a nut engaged upon 15 said bolt to force the clamping members into engagement upon opposite edges of the shoe and cause said members to exert a wedging action against the calk body to force the same into biting frictional engagement with 20 the bottom face of the shoe.
5. A detachable horseshoe calk including a calk body provided with a bolt receiving opening, clamping members each having a longitudinal slot, a bolt extending through 25 said opening and slots, said clamping members being shiftable upon the bolt longitudinally of the calk body, and a nut threaded upon said bolt to force the clamping members into engagement against the opposite 30 edges of the shoe, said clamping members and the calk body being provided with co-acting means whereby said body is forced into biting frictional engagement with the bottom face of the shoe. 35
- 40 6. A detachable horseshoe calk including a calk body having laterally projecting flanges on one end, the said end of the calk body having a roughened face for engagement with the bottom face of the shoe, separable clamping members each provided with bendable lugs for engagement against 45 said flanges whereby the latter may be forced against the face of the shoe, and means for holding the calk body and clamping members in assembled relation and clamping the latter against the opposite 50 edges of the shoe bar.
7. A detachable horseshoe calk including a calk body having a roughened end face for biting engagement against the bottom face 55
- of the shoe, said end of the calk body being provided with laterally projecting flanges thereon, separable clamping members, one of said members being provided with means adapted to be forcibly engaged against said flanges to cause the roughened face thereof to bite into the shoe bar, and means for holding the calk body and clamping members in assembled relation and clamping said members against the opposite edges of the shoe. 60
8. A detachable horseshoe calk including a calk body having convergently inclined side faces, one end of said body being provided with laterally projecting flanges thereon, separable clamping members also having 65 inclined faces to co-act against the respective inclined faces of the calk body, means for holding the calk body and clamping members in assembled relation and clamping said members against the opposite edges 70 of the shoe, said members exerting a wedging action upon the calk body to cause the same to grip the bottom face of the shoe, and means on each of the clamping members adapted to be forcibly projected against said 75 flanges to effect a further gripping action of the same upon the shoe.
9. A detachable horseshoe calk including a calk body having opposite convergently inclined side faces, separable clamping members each provided with inclined faces, to co-act against the inclined faces of said body, each of said members having a longitudinal 80 projection extending beyond one end of the calk body and the inner faces of said projections having longitudinally extending teeth formed thereon for gripping engagement against the opposite edges of the shoe, means for holding the body and clamping members in assembled relation, said members being provided with means affording longitudinal adjustment of the same with respect to the calk body, said holding means including a clamping bolt and nut whereby 85 said members are forced into gripping engagement upon opposite edges of the shoe, said members exerting a wedging action upon the calk body and causing the same to grip the bottom face of the shoe. 90
- In testimony whereof I hereunto affix my 95 signature in the presence of two witnesses.
